UNITED STATES PATENT OFFICE

2,140,474

TELEPHONE BOOTH

Willard A. Gulickson, Chicago, Ill., assignor to
 Churchill Cabinet Company, Chicago, Ill., a
 corporation of Illinois

Application September 16, 1938, Serial No. 230,197

7 Claims. (Cl. 200—54)

The present invention relates to telephone booths, and is particularly concerned with ventilating and lighting arrangements for telephone booths, which are adapted to be controlled or actuated by means of the opening and/or closing of the door of the booth.

One of the objects of the invention is the provision of an improved telephone booth of the type having a door-controlled lighting and ventilating arrangement, in which the structure of the booth is so simplified that it is more economical, so that it may be placed within the reach of a larger number of purchasers.

Another object of the invention is the provision of an improved telephone booth door and control switch structure in which the control of the ventilation and lighting is more critical than in the devices of the prior art.

Another object of the invention is the provision of an improved door control switch structure for telephone booths in which the switch is adapted to be actuated at a predetermined point in closing or opening the door.

Another object is the provision of an improved door-actuated switch structure for telephone booths which is substantially noiseless and which is more readily available for inspection and repair.

Other objects of the invention will be apparent from the following description and the accompanying drawings, in which similar characters of reference indicate similar parts throughout the several views.

Referring to the drawings,

Fig. 1 is a fragmentary vertical sectional view, taken from the inside of the telephone booth at the top, embodying the invention;

Fig. 2 is a fragmentary vertical sectional view, taken on the plane of the line 2—2 of Fig. 1, looking in the direction of the arrows;

Fig. 3 is a horizontal sectional view, taken on the plane of the line 3—3 of Fig. 1, looking in the direction of the arrows;

Fig. 4 is a full sized fragmentary sectional view, taken on the plane of the line 4—4 of Fig. 3, looking in the direction of the arrows;

Fig. 5 is a wiring diagram.

Referring to Fig. 1, the telephone booths embodying the invention are preferably provided with the side walls 11, 12, rear wall 13, front wall 14, double ceiling 15, 16, and the front wall may be provided with a ventilating electric fan driven by a motor 17.

The motor 17 is connected in parallel with the electric light 18 by a pair of conductors 19, 20,

which are controlled by means of the switch 21. The switch 21 is preferably a snap switch of the button-actuated type, which is provided with spring means for urging the switch to open position. It has a housing 22 and a threaded shank 23 and a projecting button 24. The threaded shank may be conveniently mounted on a metal plate 25 by means of a pair of lock nuts 26, so that the switch may be secured in place in a recess 27 by a pair of wood screws 28.

The booth is provided with a door frame comprising the front wall 14 and the stiles 30, 31, and the door may comprise a pair of sections 32, 33 hingedly mounted at 34 and hinged to the stile 30 by means of the hinge 35.

In order to guide the door into its proper position, the upper part of the door section 33 is provided with a guide member 36 comprising a metal bracket having an attaching flange 37, which is secured to the door section 33 by wood screws 38.

The guide member 36 has an upwardly extending cylindrical trunnion 39, which may be provided with a fiber block 40, having a bore 41 fitting on the trunnion 39. The guide member 36 is provided with a stop shoulder 42, upon which the block rests. The block 40 is preferably substantially rectangular in plan and elevation, and is adapted to be slidably received in a guide channel 43, which is carried by a transverse frame member 44.

The transverse frame member 44 is provided with a slot 45 for receiving the channelled metal guide member 43, which has a pair of parallel flanges 46, 47 joined by a body flange 48. The body flange 48 is provided with an aperture 49 for passing the threaded shank 23 of the switch 21, and the transverse frame member 44 is provided with a bore 50 and with a recess 21 for receiving the parts of the switch 21. Thus the button 24 may project into the guide channel 43 in a vertical direction.

The fiber block 40 is preferably provided with a rounded camming surface 51 at each of its upper corners, and the block is of less depth than the channelled member, so as to provide space for the switch actuating arm 52. The switch actuating arm 52 may comprise a resilient metal member having an attaching flange 53 provided with an aperture 54 for receiving a wood screw 55, which secures it in the guide channel 43 and frame member 44.

The guide channel is provided with a registering aperture 56 for the wood screw 55. The width of the switch actuating arm 52 is preferably slightly less than the width of the guide channel 55.

43, and the switch actuating arm is provided with an offset portion 57 and a longitudinally extending body portion 58. At its left end (Fig. 4) it is provided with an upwardly curved end, providing 5 a camming surface 59, and the extreme end 60 is adapted to engage the body flange 48 of the guide channel 43. The normal position of the switch actuating arm 52 when it is not engaged by the block 49 is shown in dot-dash lines in Fig. 4, 10 at which time the switch button 24 is in its extended position so that the switch 21 is in open position. This is also the position of the parts, as shown in Fig. 3, in dotted lines, with the door in folded and open position at the left.

15 When the switch is in this condition and the door is open, both the motor 17 and electric light 18 are turned off, as no ventilation or illumination is required when the door is open and the booth is not in use. The offset 57 is such that 20 when the block 49 has progressed to the point shown in Fig. 4 the switch actuating arm 52 has its point 60 forced into engagement with guide channel 43, and the push button 24 has been actuated by the intermediate body portion 58 of 25 the switch arm 52 to closed position. This energizes the motor 17 and the electric light 18 simultaneously, and it will thus be observed that when the door is moved to closed position (Fig. 3, full lines), the ventilation fan is then actuated 30 and the booth is illuminated.

The cost of a switching arrangement constructed according to the invention is a fraction of that of the devices of the prior art, in which the door section was provided with an upwardly extending 35 arm for actuating a switching arrangement located between the ceilings 15 and 16. The ventilation and illumination are more positively controlled and more certainly actuated at a predetermined point in the movement of the door. 40 There is no ventilation or illumination unless the door is substantially closed, and thus it is assured that the switch will not be left closed by users who leave the door in partially closed positions.

45 The guide channel 43 is provided at its left end (Fig. 3) with a felt stop block 53, which is adapted to engage the block 49 when the door is in open position, to absorb the shock of stoppage of the door sections when the door has been completely opened.

50 While I have illustrated a preferred embodiment of my invention, many modifications may be made without departing from the spirit of the invention, and I do not wish to be limited to the 55 precise details of construction set forth, but desire to avail myself of all changes within the scope of the appended claims.

Having thus described my invention, what I 60 claim as new and desire to secure by Letters Patent of the United States, is:

1. In a telephone booth, the combination of a 65 booth having side walls and ceiling, with a door comprising a pair of sections pivoted together, one of the sections being pivoted to the wall of the booth, a guide member carried by the other of said sections, and having a part extending into a channelled guiding member, said channelled guiding member extending transversely and 70 backwardly from the closed position of the door, and switch means located in said channelled member and adapted to be actuated by said part when the door has reached substantially closed position.

2. In a telephone booth, the combination of a 75 booth having side walls and ceiling, with a door

comprising a pair of sections pivoted together, one of the sections being pivoted to the wall of the booth, a guide member carried by the other of said sections, and having a part extending into a channelled guiding member, said channelled guiding member extending transversely and backwardly from the closed position of the door, and switch means located in said channelled member and adapted to be actuated by said part when the door has reached substantially closed position, said switch means comprising a switch having an actuating member urged to open switch position and projecting through an aperture in said channelled guide member. 5

3. In a telephone booth, the combination of a 15 booth having side walls and ceiling, with a door comprising a pair of sections pivoted together, one of the sections being pivoted to the wall of the booth, a guide member carried by the other of said sections, and having a part extending into a channelled guiding member, said channelled guiding member extending transversely and backwardly from the closed position of the door, and switch means located in said channelled member and adapted to be actuated by said part 20 when the door has reached substantially closed position, said switch means comprising a switch having an actuating member urged to open switch position and projecting through an aperture in said channelled guide member, and said 25 part comprising a trunnion provided with a non-metallic block slidably engaged in said channelled member and adapted to actuate said switch. 30

4. In a telephone booth, the combination of a 35 booth having side walls and ceiling, with a door comprising a pair of sections pivoted together, one of the sections being pivoted to the wall of the booth, a guide member carried by the other of said sections, and having a part extending 40 into a channelled guiding member, said channelled guiding member extending transversely and backwardly from the closed position of the door, and switch means located in said channelled member and adapted to be actuated by said part 45 when the door has reached substantially closed position, said switch means comprising a switch having an actuating member urged to open switch position and projecting through an aperture in said channelled guide member, and said 50 part comprising a trunnion provided with a non-metallic block slidably engaged in said channelled member and adapted to actuate said switch, said block slidably engaging a resilient metal arm, and said metal arm engaging said 55 switch member. 50

5. In a telephone booth, the combination of a two-section door with a channelled guide member, and a guide member carried by one of the sections of said door, and having a trunnion, said 60 trunnion carrying a block slidably mounted in said guide member, a resilient switch arm located above said block in said channelled member and extending substantially parallel to said channelled guide member, and switch means adapted 65 to be actuated by said arm when the block has reached predetermined position.

6. In a telephone booth, the combination of a two-section door with a channelled guide member, and a guide member carried by one of the sections of said door, and having a trunnion, said 70 trunnion carrying a block slidably mounted in said guide member, a resilient switch arm located above said block in said channelled member and extending substantially parallel to said 75

channelled guide member, and switch means adapted to be actuated by said arm when the block has reached predetermined position, said switch means comprising a snap switch of the 5 button-actuated type, spring-urged to open switch position, said button being engaged by said resilient arm.

7. In a telephone booth, the combination of a two-section door with a channelled guide member, and a guide member carried by one of the 10 sections of said door, and having a trunnion, said trunnion carrying a block slidably mounted in said guide member, a resilient switch arm located above said block in said channelled mem-

ber and extending substantially parallel to said channelled guide member, and switch means adapted to be actuated by said arm when the block has reached predetermined position, said switch means comprising a snap switch of the 5 button-actuated type, spring-urged to open switch position, said button being engaged by said resilient arm, said arm having a laterally curved end portion adapted to engage said channelled guide member, and having a resilient offset 10 portion adjacent an attaching flange which is secured to said channelled guide member.

WILLARD A. GULLICKSEN.
